[57] CLAIM

The ornamental design for a bicycle frame, substantially as shown and described.

DESCRIPTION

FIG. 1 is a side elevational view of a bicycle frame showing my new design;

FIG. 2 is a top plan view thereof;

FIG. 3 is a rear elevational view thereof; and

FIG. 4 is a front elevational view thereof.

The broken lines in FIG. 1 are for illustrative purposes only.

F / G. 1

FIG. 4
